UNITED STATES PATENT OFFICE.

MICHAEL J. MALOY, OF WOODLAND, MAINE.

EXPANSION-MANDREL.

1,232,704.

Specification of Letters Patent.

Patented July 10, 1917.

Application filed June 2, 1916. Serial No. 101,420.

To all whom it may concern:

Be it known that I, MICHAEL J. MALOY, a citizen of the United States, residing at Woodland, in the county of Washington and 5 State of Maine, have invented a new and useful Expansion-Mandrel, of which the following is a specification.

The device forming the subject matter of this application is an expansion mandrel 10 adapted for holding ring-burs of the sort employed in recutting or grinding stones of the kind used for reducing pulp-wood into wood-pulp.

The invention aims to provide novel means 15 whereby the sleeve may be expanded to hold the ring-bur, and to provide novel means whereby the device may be lubricated.

With the above and other objects in view which will appear as the description proceeds, the invention resides in the combination 20 and arrangement of parts and in the details of construction hereinafter described and claimed, it being understood that changes in the precise embodiment of the invention 25 herein disclosed can be made within the scope of what is claimed, without departing from the spirit of the invention.

In the accompanying drawings:—

Figure 1 shows in longitudinal section, an 30 expandible mandrel constructed in accordance with the present invention;

Fig. 2 is a cross section of the device as shown in Fig. 1;

Fig. 3 is a side elevation showing the male 35 expansion element;

Fig. 4 is a side elevation showing the expandible sleeve; and

Fig. 5 is a side elevation showing the female 40 expansion element.

In the accompanying drawings, the numeral 1 indicates a ring bur of the kind used in grinding wood pulp stones. Disposed 45 within the ring bur 1 is a sleeve 2 which is slit longitudinally as indicated at 23, in order that it may be expandible. The bore of the sleeve 2 tapers from the ends of the sleeve toward the intermediate portion thereof, as indicated at 3, so that the sleeve is thickest about midway between its ends. In

50 order to facilitate the expansion of the sleeve 2, the same is provided about midway between its ends with longitudinal slits 4 intersected by enlarged openings 5. Owing to the construction above outlined, the sleeve 55 is made yieldable and expandible in its thickest part.

Mounted in one end of the sleeve 2 is a male coupling element 6 including a head 7 which is tapered as shown at 8 to coöperate with one of the tapered portions 3 of the bore of the sleeve 2. The head 7 of the male expansion element is provided with a stem 9 terminated in a tapered tip 15. The stem 9 of the male expansion element is circumscribed by threads 10. In one end of the male expansion element 16 are formed one or more oil bores 17, closed at their outer ends with screw plugs 24 or otherwise. The bores 17 open laterally, as indicated at 18, into a circumscribing recess formed in the interior of the male expansion element 6.

The numeral 19 indicates a female expansion element threaded as shown at 20 to coact with the threads 10 of the male expansion element 6. The female expansion element is externally tapered as shown at 21, to coact with one of the tapered portions 3 of the bore of the sleeve 2. The female expansion element 19 includes an end wall 26 journaled on the tip 15 of the male expansion element 6. In the end wall 26 of the male expansion element, wrench seats 22 are formed.

Disposed within the male expansion element 6 and the female expansion element 19 is a bushing 11 which if preferred may be made of brass. The bushing 11 is provided with small perforations 12 communicating with the circumscribing internal recess 14 of the male expansion element 6.

Having thus described the invention, what is claimed is:—

1. In a device of the class described, a sleeve provided at its ends with inwardly tapered bores; a male expansion element including a head, a threaded stem projecting from the head and of less diameter than the stem, the stem having a reduced tip, the head being tapered to coöperate with one bore; and a female expansion element threaded on the stem, the female expansion element being externally tapered to coöperate with the other of said bores, and including the end wall journaled on the tip.

2. In a device of the class described, a sleeve provided at its ends with inwardly tapered bores, the sleeve being provided intermediate its ends with an opening therethrough, there being slots extended longitudinally of the sleeve and prolonged therethrough, the slots communicating with the opening and lying on opposite sides of the

opening; and a male expansion element including a head and a threaded stem of less diameter than the head, the head being tapered to coöperate with one of the bores; 5 and a female expansion element threaded on the stem, the female expansion element being externally tapered to coöperate with the other of the bores.

In testimony that I claim the foregoing as my own, I have hereto affixed my signature 10 in the presence of two witnesses.

MICHAEL J. MALOY.
